OIL BURNING DEVICE

Hilmer F. Rodler, Woodcliff, N. J., assignor, by direct and mesne assignments, to Oil Equipment Laboratories, Inc., a corporation of New Jersey

Application November 2, 1932, Serial No. 640,802

2 Claims. (Cl. 158—77)

This invention relates to devices for use in connection with furnaces for heating dwellings, and more particularly to such devices which burn a fluid fuel.

It is an object of the invention to provide a fluid-fuel burning apparatus, which may be readily and conveniently installed in the usual household furnace, and which can be easily removed and replaced for repairs or other purposes whenever necessary.

10 A further object is the provision of an oil burning apparatus having rotary means for atomizing the oil and effecting an efficient mixture of atomized oil and air.

15 A further object is the provision of an oil burning apparatus having means for regulating the volume of air passing therethrough, and having also means to regulate the velocity of the mixture of atomized oil and air and controlling same in a fixed direction.

20 A further object is the provision of an oil burning unit which is not physically connected with a hearth structure or other parts of a furnace whereby the unit will not be heated by conduction of heat from the hearth or furnace parts 15 and suspended in such a manner as to give a full floating power effect which absorbs vibrations at all speeds, A. C. hum of the motor and giving an absorbing cushion to the shocks received by motor bearings when motor starts under load.

25 A further object is the provision of an oil burning unit having an atomizing device which is shielded from the heat of burning oil, the shield of the atomizing device forming the means for directional control of the air.

30 A further object is the provision of novel means in an oil burning unit to take care of an overflow of oil in the event of non-operation of an atomizing device or other parts in the unit.

35 These and other advantageous objects, which will later appear, are accomplished by the simple and practical construction and arrangement of parts hereinafter described and exhibited in the accompanying drawings, forming part hereof, and in which:

40 Fig. 1 is an elevational view in section of oil burning apparatus embodying my invention.

45 Fig. 2 is an enlarged sectional view of an atomizing device employed in the oil burning apparatus,

50 Fig. 3 is an elevational view of an oil burning apparatus embodying a modified form of the invention designed to use heavy oils,

55 Fig. 4 is a sectional view of an atomizing device used in the modified form,

Fig. 5 is a sectional view taken on line 5—5 of Fig. 3,

Fig. 6 is a sectional view taken on line 6—6 of Fig. 3,

Fig. 7 is a sectional view taken on line 7—7 of Fig. 3, and

Fig. 8 is a general diagrammatic view showing the path of flow of oil and air in the oil burning apparatus.

Referring to the drawings, the oil burning apparatus comprises a vertically mounted motor 8 having a shaft 7. Mounted on the upper end of the motor is a cylindrical block 5 having a skirt 9 provided with inclined passages 11 to which oil is introduced by a pipe 10 communicating therewith. The inclined passages 11 lead to an annular oil chamber 12, also formed in the block 5, one wall 13 of the chamber 12, surrounding the shaft 7.

Resting on the upper edge of wall 14 of the chamber 12 is a flange 19 of an annular trough member 15, the walls 20 and 18 of which are spaced respectively from the walls 13 and 14. Positioned in the member 15 is a cylindrical flange 50 of a head 21, the latter having a central core 25 28 threadedly connected to the end of shaft 7. The flange 50 is externally threaded at 24 and internally threaded at 25 for a purpose herein-after explained.

The internal wall of the flange 50 is flared at 22 providing a throat 27. The head 21 is provided with a plurality of passages 29 communicating with the throat 27, and the upper end of head 21 is bevelled to provide a sharp edge 30.

Integral with head 21 are a plurality of spaced 35 lugs 31 to which is secured a tubular member 32 which is curved at its upper end to provide a right-angled flange 33 having a sharp edge 34 on its upper surface. These lugs not only act as a support for the outer tubular member and provide air passages, but also act as a small inductive fan. The member 32 is spaced from the head 21, except where it engages lugs 31, to provide an air passage 44, the spaces between the lugs providing air passages 45. Secured to the member 32 by a threaded nut 38 is a fan 39.

The tubular member 32 is covered by a plate 36, which is spaced from the flange 33 and attached to a shaft 35, the latter being threadedly connected to core 28, (see Fig. 2).

Attached to the block 5 are spaced struts 46, integral with a cylindrical base 40, upon which is mounted a hood 41 having its upper portion 42 cylindrical in shape. A collar 48 is threadedly mounted on block 5, and has integral therewith 55

a plate 47 spaced from the lower edge of the base 46. By adjusting the plate 47, the volume of air entering the hood may be controlled.

In operation, oil is supplied by the pipe 10 to the passages 11, and thence to the chamber 12 in which the oil rises to the upper edge of wall 20, and falls over the edge when the surface tension has been overcome. The oil is then picked up by the threads 25 on the flange 50, and thrown upwardly against the inclined surface 22 and into the passages 29, it being understood that the motor is in operation and the parts are rotating at a predetermined speed. The threads 24 force an air stream downwardly, and thus prevent the leakage of oil upwardly over the inner surface of wall 18 of the trough member 15.

In the event that the oil should accumulate in the chamber 12 excessively, due to improper functioning of the apparatus, it will rise over the upper edge of wall 13 and fall down along the shaft 7 into a chamber 60 in the block 5, and thence through a passage 61 to a gutter 16 integral with and surrounding the block. The gutter 16 communicates with a tube 17, through which the excess oil is drained into any suitable receptacle, such as a bucket, or the like (not shown).

Referring again to the head 21, as the oil moves up the walls of passages 29, it strikes the bevelled edge 30 and is broken up or atomized, at the same time the volatile portions are mixed with the air stream, while the heavier portions of the oil move up the walls of member 32. When the stream of air and volatile portions of the oil strikes the plate 36, the oil partially condenses, but is immediately atomized again when it passes over the edge 37 of plate 36. The heavier particles of oil which move up the walls of member 32 are atomized as they pass over the sharp edge 34 of flange 33; and two streams of atomized oil and air meet and are completely mixed at a short distance from the edge of plate 36, at which time the fuel is ignited.

Attached to the lower end of shaft 7 is a centrifugal governing device 50, which forces a collar 51 downwardly against the action of a spring when the shaft has attained a speed sufficient to cause the atomizing structure to function properly. The downward movement of collar 51 actuates a lever 52 to move a valve stem 53 to raise a valve head 54 to allow oil to flow from pipe 55, connected with a source of supply, to the pipe 10. This arrangement prevents the flow of oil to the atomizer until the latter has attained a speed sufficient to enable it to operate properly.

In Fig. 4 is shown a modified form of the invention adapted for use with heavy oils. In this form a head 73 is provided with a plurality of passages 74, for example nine in number, through which oil is drawn as above described in connection with Fig. 2, the head having a flange 70 provided with threaded portions 71 and 72 similar to the flange 50 with its threaded portions 24 and 25. The head is mounted on the end of motor shaft 75 and has threaded to its upper end a tubular member 81, whose outer wall is flush with the outer wall of the head. The member 81 has its upper end flanged and is covered by a plate 84, which is attached to a shaft 90 connected with the head 73. A collar 91 is threaded onto the head 73, and secures thereto a second tubular member 78 to which is attached a fan 92. The head 73 has nine passages 74, six of which communicate with inclined passages 76 which lead to the space 77 between the walls of tubular members 81 and 78.

When oil is drawn into passages 74, the major portion will pass through passages 76 into the space 77 where it will be mixed with the air forced therein through the apertures 93 in the bottom of member 78. This portion of the oil moves upwardly in the space 77, the volatile portion of the oil being condensed as it strikes the underside of the flange of member 81, and re-atomized as it passes over the edge 82, while the heavier portion of the oil is atomized as it passes over the sharp edge 80 of the flange 79.

The oil that passes up along the inner wall of member 81 is partially atomized and partially in a liquid state. The atomized portion condenses on the under side of plate 84 and is atomized as it passes over the edge of the plate 84. The liquid portion is atomized as it passes over the edge 83 on the upper side of the flange on member 81. The several streams of atomized oil and air are then completely mixed with a whirling motion at a short distance from the edges of plate 84 and member 81, at which point they are ignited.

Referring to Fig. 1, it will be seen that the atomizing structure and motor, for both forms of the invention, are mounted on a frame having vertical supports 103, which rest on resilient bases 101, excessive vibrations of the motor being absorbed by spring supports 102.

The oil burning apparatus is readily installed in the fire box of a furnace, a hearth of fire brick 103 being built upon the frame. The hood 41 and other parts of the atomizing structure are protected from heat by a metal casting 104 carrying an insulating material 105, and by a ring 106 which rests on the casting 104. The ring 106 has 35 a flange alongside of but spaced from the cylindrical portion 42 of the hood 41, which provides a space through an additional supply of air passes, at the same time providing an effective heat shield which at no point contacts with the hood or the atomizing apparatus, thus preventing heating of such parts by conduction. By varying the thickness of ring 106, and by adjusting the height of sharp edge 30, the velocity of the air stream can be regulated.

The general operation of the apparatus is diagrammatically shown in Fig. 8. As indicated, oil is conducted from a supply source (not shown) by a pipe 55, through a valve A to the pipe 10 to the chamber 12, where it overflows the wall 20, and is picked up by the threads 25 and thrown into the passages 29 and partially atomized. It is then mixed with air in the member 32, and finally passes out of the atomizer between plate 36 and flange 33 in a highly atomized form properly mixed with air for efficient combustion. A stream of air under high velocity is supplied by the fan in the passage between the hood 41 and the member 32.

It will be seen that the oil is first mechanically broken up as it passes over edge 30 (Fig. 2) to produce a mist through which air under high velocity is driven in direct spirals, due to the rotation of the member 32. The oil is again broken up mechanically by the edges 34 and 37 and again interrupted by an air spiral created in the passage between the hood 41 and the outer surface of member 32. The lower velocity of the air at the second breaking up of the oil at edges 34 and 37 causes a thorough mixture of atomized oil and air without forcing the mixture out with such velocity that the flame largely breaks against the fire-brick wall. With my arrangement the flame occurs a short distance from the edge 37 and the intimate mixture and the burning of the 75

oil out of contact with any surface causes complete combustion with no caking of fuel on any surface.

5 While my invention has been described specifically with reference to the burning of oil, it is obvious that it may be readily employed for the atomization and burning of any type of fluid-fuel without departing from the spirit of the invention.

10 The foregoing disclosure is to be regarded as descriptive and illustrative only, and not as restrictive or limitative of the invention, of which obviously an embodiment may be constructed including many modifications without departing 15 from the general scope herein indicated and denoted in the appended claims.

Having thus described my invention, what I claim as new and desire to secure by Letters Patent, is:

20 1. In an oil burning apparatus, a vertically mounted motor, an atomizing device connected to the shaft of the motor and rotated thereby, said atomizing device comprising a tubular member having a central core provided with a plurality of passages, means for forcing oil up through the passages in the core, means on the core for atomizing oil into a mist immediately after leaving said passages, said tubular member being spaced from the core at a plurality of points 25 to provide a plurality of passages, the rotation

of the tubular member forcing air through the last mentioned passages to mix with the oil mist, a flange at the upper end of the tubular member, a plate spaced from the flange and covering the tubular member, the oil being further atomized as it passes between the flange and plate, a hood surrounding the tubular member, and a fan for creating an air stream in the hood to mix with the atomized oil immediately after the latter passes between said flange and plate. 10

2. In an oil burning apparatus, a vertical shaft, means for rotating the shaft, an atomizing device connected to the shaft and rotated thereby, said device comprising a tubular member having a central core provided with a plurality of passages through which oil flows, means on the core for atomizing the oil into a mist immediately after the oil leaves said passages, said tubular member being spaced from the core at a plurality of points to provide a plurality of air passages, the upper end of said tubular member flaring upwardly, a plate spaced from the upper end of and covering the tubular member, the oil being further atomized as it passes over the edges of the plate and the tubular member, and means 25 for creating an air stream to mix with the atomized oil immediately after the oil passes over the edges of the plate and the tubular member.

HILMER F. RODLER. 30
